UNITED STATES PATENT OFFICE.

HAROLD H. LINDNER, OF NEW YORK, N. Y., ASSIGNOR TO MONTAGUE & CO., INC., OF NEW YORK, N. Y., A CORPORATION OF NEW YORK.

DESIGN FOR A VALANCE.

61,272.

Specification for Design.

Patented July 25, 1922.

Application filed April 1, 1922. Serial No. 1,487. Term of patent 7 years.

To all whom it may concern:

Be it known that I, HAROLD H. LINDNER, a citizen of the United States of America, residing in the city, county, and State of New York, have invented a new, original, and ornamental Design for a Valance, of which the following is a specification, reference being had to the accompanying drawing, forming part thereof.

The figure is a view of a portion of a valance showing an embodiment of my new design:

I claim:— The ornamental design for a valance, substantially as shown.

HAROLD H. LINDNER.
